(57) **CLAIM**

The ornamental design for an automotive door panel accessory, as shown and described.

DESCRIPTION

FIG. 1 is a perspective view of a first embodiment of an automotive door panel accessory showing my new design. FIG. 2 is a front elevational view thereof.

FIG. 3 is rear elevational view thereof.

FIG. 4 is a right-side elevational view thereof.

FIG. 5 is a left-side elevational view thereof.

FIG. 6 is a top plan view thereof.

FIG. 7 is a bottom plan view thereof.

FIG. 8 is a perspective view of a second embodiment of the automotive door panel accessory, the second embodiment being a mirror image of the first embodiment, with no patentable distinction between the first and second embodiments.

FIG. 9 is a front elevational view thereof.

FIG. 10 is rear elevational view thereof.

FIG. 11 is a right-side elevational view thereof.

FIG. 12 is a left-side elevational view thereof.

FIG. 13 is a top plan view thereof; and,

FIG. 14 is a bottom plan view thereof.

The broken lines throughout the drawings indicate environmental elements, such as zippers, grommets, and stitching, that form no part of the claimed design.
